CLAIM

The ornamental design for a modular entertainment system with movable electronic components, substantially as shown and described.

DESCRIPTION

FIG. 1 is a top plan view of a modular entertainment system with movable electronic components showing my new design;

FIG. 2 is a front elevational view of FIG. 1;

FIG. 3 is a rear elevational view of FIG. 1;

FIG. 4 is a left side elevational view of FIG. 1; and,

FIG. 5 is a right side elevational view of FIG. 1.
